UNITED STATES PATENT OFFICE.

ERNEST P. PRATOR, OF LEEPER, MISSOURI, ASSIGNOR OF ONE-THIRD TO JOHN T. FREDRICKS, OF LEEPER, MISSOURI, AND ONE-THIRD TO JOHN R. STEPHENS, OF ST. LOUIS, MISSOURI.

AUTOMATIC SHUT-OFF FOR WATER GAUGES.

Application filed March 3, 1921. Serial No. 449,584.

My invention relates to improvements in automatic shut-offs for water gauges and similar devices wherein it is desirable to shut off the fluid pressure in the event of accidental leakage from the device. One of the objects is to produce a device which will shut off the flow of water and steam to a water gauge when the glass becomes cracked or broken.

10 A further object is to construct a shut-off for water gauges, which when the broken glass is replaced will automatically open so that the gauge will again be placed in use.

15 A still further object is to construct a shut-off for water gauges which is so constructed that the replaced glass will first be heated before the boiler pressure and hot water are permitted to enter the same.

In the drawings:

20 Fig. 1 is a side elevation of my device showing the same secured to a boiler sheet.

Fig. 2 is an enlarged longitudinal section of the upper member of my device.

25 Fig. 3 is an end view viewing the same from the end which is inserted in the boiler sheet.

Fig. 4 is an enlarged view viewing the same in the opposite direction.

30 Fig. 5 is a side elevation of the lower member made use of.

Fig. 6 is an enlarged longitudinal sectional view of the same.

35 Fig. 7 is an end view of the upper central member showing the valve seat and the notch for permitting the entrance of steam to the water glass for preheating it.

Fig. 8 is a side elevation of the combined lever and indicator.

Fig. 9 is an end view of the upper valve.

40 Fig. 10 is a side elevation of one of the valves; and

Fig. 11 is an end view of the same looking in the direction indicated by the arrow in Fig. 10.

45 In the construction of my device I employ an upper central member 12. This member is provided on one end with the screw-threaded projection 13. This screw-threaded projection is provided with a valve seat 14 and a central opening 15. The opening 15 communicates with a chamber 16 formed in the member 12. The valve seat is provided with a notch or recess 17, the purpose of which will be explained later. Secured on the

55 screw-threaded projection 13 is a sleeve 18, which has its end screw-threaded, as at 19, to permit its insertion into a boiler sheet. The sleeve 19 is provided with the opening 21, which communicates with an enlargement 22 and in this enlargement is located the 60 valve 23. This valve has a tapered face 24, which is adapted to seat against the valve seat 14 and prevent the leakage of steam. Through the valve 23 is formed an opening 25, the purpose of which is to permit steam 65 from the boiler to pass through the passage-way 15 and into the chamber 16. This passage of steam, however, will only take place when the opening 25 is so turned as to register with the notch 17. When this opening 70 does not register with the notch 17, the valve seat 14 closes this opening and no escape of steam is possible. Formed integral with the valve 23 is a portion 26. This portion has flattened faces 27, as indicated in Fig. 75 11. These flattened faces are joined by the curved faces 28, which fit snugly within the bore 15 and act as a guide for the valve 23. The flattened faces, however, allowing sufficient space for the free passage of steam into 80 the chamber 16. Formed integral with the portion 26 is a valve stem 29. This valve stem is provided with a cylindrical opening 30, which opens into the chamber 16 (see Fig. 2). The valve stem 29 is provided on its 85 rear end with the piston 31, which is secured thereto by means of the nut 32. The piston 31 is located in the cylinder 33. This cylinder is open at its inner end and is provided at its inner end with the valve seat 34 90 against which the bevelled edge 35 of the piston rests. This prevents any leakage when the piston is engaged with the valve seat 34. The opposite end of the cylinder 33 is closed by means of a nut or cylinder head 95 36. Formed integral with the cylinder 33 is an arm 37, which in turn is formed integral with a nut or collar 38. This collar being secured to the screw-threaded projection 39 formed integral with the central 100 member 12. Extending from the projection 39 is a gland 40 over which a packing nut 41 is secured. This is for the purpose of packing the valve stem 29 and preventing leakage. Secured on the valve stem 29 is 105 a combined lever and indicator 42. This being for the purpose of indicating whether the valve is open or closed and is also for

the purpose of rotating the valve 25 so as to remove any scale which might form on the valve or valve seat and prevent its seating properly. Formed integral with the central member 12 is a screw-threaded sleeve 43, which is adapted to receive the lock nut 44 for locking the upper portion of the water glass 45 in position. This sleeve is provided with a passageway 46, which communicates with the chamber 16. The lower member consists of a central member 47, which is likewise provided with a screw-threaded projection 48 having a valve seat 49 located therein. Secured to this screw-threaded projection is a sleeve 50 having a screw-threaded end 51 by which the lower portion of the device is attached to a boiler. The central member 47 is provided with a chamber 52 and with a passageway 53, by means of which water is admitted to the chamber 52. The sleeve 50 is provided with a passageway 54 and the enlargement 55 through which the water from the boiler may enter. In the enlargement 55 is located a valve 56, which is provided with the bevelled surface 57, which is adapted to come in contact with the seat 49 and close off the water from the boiler. The central member 47 is provided with a screw-threaded projection 58, which receives the lock nut 59 for locking the lower end of the water glass 45 in position. The projection 58 is provided with a passageway 60, which communicates with the chamber 52. Formed integral with the valve 56 is the enlargement 61 and valve stem 62. These parts 61 and 62 are formed identically with the parts 27, 28 and 29 of the valve device shown in Fig. 10, as are also the piston 63 and nut 64. The cylinder 65 is also provided with a valve seat 66. This valve seat performs the same function as the valve seat 34. The cylinder 65 is closed by means of a cylinder head or nut 67 and secured in this cylinder head is a drain cock 68. This drain cock is for the purpose of cleaning out the cylinder 65 since by opening it water will be driven through the passageway 69 formed in the valve stem 62 and drive out accumulated sediment. The cylinder 65 is secured to the central member by means of the yoke 70, which is formed integral with the nut or collar 71, which is screw-threaded on the projection 72 formed integral with the central member. The valve stem 62 is also packed against leakage by means of the gland 72^a and packing nut 73. Mounted on the valve stem 62 is a combined lever and indicator 74, which is for the same purpose as the lever 42. Formed in the underside of the central member and communicating with the chamber 52 is a screw-threaded passage 75 in which is seated the valve 76.

It will be noted that the passage 77 in the 65 valve is of greater diameter than the inside

diameter of the water glass 45. The purpose of this is that when the valve 76 is fully opened all of the pressure in the glass 45 is released and the valves act the same as if the glass 45 were broken. In this way the device can be tested at any time so as to ascertain whether or not the automatic valves are functioning properly. The valve 76 also allows the cleaning out of the chamber 52 since the valve 56 can be unseated by means of the lever 74 and allow water from the boiler to flush out the chamber 52.

The operation of my device is as follows:

After the gauge has been installed on the boiler and the water turned in until the desired level of water is reached heat is applied to the boiler, the valves are unseated by moving the levers 42 and 74 backward and letting them hang in the position in Fig. 1; as the water becomes heated the entire apparatus will gradually attain the proper temperature. At this time the upper member, as well as the passage 30 and cylinder 33, will be filled with steam, while the lower member together with the passage 69 and cylinder 65 will be filled with hot water. Both of the members are subjected to the boiler pressure. In the event the glass 45 breaks or cracks, the pressure inside of the glass and in the cylinders 33 and 65 will be released and the boiler pressure will seat the valves 23 and 56, thus closing off the steam and water supply from the boiler, with the exception of a thin stream of steam which passes through the opening or port 25. This steam issuing will also be an indication that there is something wrong with the system, in the event that the glass is not totally destroyed. When it is desired to replace a broken or defective glass the lever 42 is turned so as to bring the opening 25 out of alignment with the notch 17, when this flow of steam will cease. The new glass is then inserted and the lever 42 again turned in the position shown in Fig. 1; or in other words, the handle straight down. This will allow steam to enter through the port 25 and notch 17, which steam will gradually fill the entire device; that is, the device to the front of the valves 23 and 56, and as the device gradually attains boiler pressure the glass becomes warmed and when boiler pressure is reached, the pressure in the cylinders 33 and 65 will automatically unseat the valves 23 and 56 and restore the complete operation of the device. In this way it is possible for the engineer to install a new water glass without any danger of being scalded, and also, he may leave the glass directly after it has been installed and let the automatic opening place the glass into use when it has become properly warmed. This placing in use of a new glass at present requires considerable care, as the glass is liable to crack if the steam or water pressure is

turned on suddenly, which causes a sudden and unequal rise in temperature. While I have shown my device having both upper and lower members attached directly to a boiler sheet, it is obvious that there may be various other connections made so that the water glass or gauge can be placed in any desired position without departing from the spirit of my invention.

10 Having fully described my invention, what I claim is:

1. In a device of the character described, a water glass, upper and lower conductors whereby the ends of said water glass are placed in communication with a boiler, check valves adapted to control communication between said ends and the boiler, said check valves being movable to their closed positions in response to a rapid discharge of fluid therepast, and fluid-actuated valve-opening means whereby said valves are automatically opened in response to fluid pressure in said water glass, said means including pressure-receiving members carried by the respective valves and said conductors having passageways through which pressure is transmitted to said pressure-receiving members, and one of said valves having a port whereby said water glass is placed in communication with the boiler when said valves occupy their closed positions, so as to provide for the transmission of fluid pressure to said pressure-receiving members.

2. In a device of the character described, a water glass, upper and lower conductors whereby the ends of said water glass are placed in communication with a boiler, check valves in said conductors adapted to control communication between said ends and the boiler, said check valves being movable to their closed positions in response to a rapid discharge of fluid therepast, and fluid-actuated valve-opening means whereby said valves are automatically opened in response to fluid pressure in said water glass, said means including fluid-actuated members and said conductors being provided with passageways through which fluid pressure is transmitted from said water glass to said fluid-actuated members, and there being a restricted steam outlet through which steam escapes to said water glass when the valves occupy their closed positions.

3. In a device of the character described, a water glass, upper and lower conductors whereby the ends of said water glass are

placed in communication with a boiler, check valves in said conductors adapted to control communication between said ends and the boiler, said check valves being movable to their closed positions in response to a rapid discharge of fluid therepast and fluid-actuated valve-opening means whereby said valves are automatically opened in response to fluid pressure in said water glass, said means including pistons each connected to one of said valves, and cylinders in which said pistons are mounted, there being a restricted steam outlet through which steam escapes to the water glass when the valves occupy their closed positions, and said conductors being provided with passageways through which fluid pressure is transmitted from said water glass to said cylinders.

4. In a device of the character described, a water glass, upper and lower conductors whereby the ends of said water glass are placed in communication with a boiler, check valves arranged in said conductors to control communication between said ends and the boiler, said check valves being movable to their closed positions in response to a rapid discharge of fluid through said conductors, automatic valve-opening means whereby said check valves are moved to their open positions, and manually operated oscillatory members associated with said means to permit manual operation of said check valves, each of said manually operated members being rigidly secured to one of said valves so as to permit oscillation of the valves when they occupy their closed positions.

5. In a device of the character described, a water glass, upper and lower conductors whereby the ends of the water glass are placed in communication with a boiler, and upper and lower check valves arranged in said conductors, said check valves being movable to their closed positions in response to a rapid discharge of fluid through said water glass, the upper check valve having a restricted port permitting leakage of steam from the boiler when said upper check valve is closed, the seat for said upper check valve being provided with a closure for said restricted port, and means for turning said upper check valve to locate its restricted port at said closure.

In testimony whereof, I have signed my name to this specification.

ERNEST P. PRATOR.
